PORTABLE VALET

Harry C. Bullock, Aurora, Colo., assignor to Motor Valet, Inc., Denver, Colo., a corporation of Colorado

Filed May 25, 1964, Ser. No. 80,134

Term of patent 3½ years

(Cl. D87—5)

FIG. 1.

FIG. 3.

FIG. 2.

The side not shown is substantially a mirror image of the side shown, and the top, bottom and rear of the design are plain and unornamented.

I claim:

The ornamental design for the portable valet, as shown and described.
